UNITED STATES PATENT OFFICE.

JAMES W. MOOREHEAD, OF ZELIENOPLE, PENNSYLVANIA.

APPLICATOR FOR BRAKE-DRESSING COMPOUNDS.

Application filed June 24, 1927. Serial No. 201,125.

My invention relates to containers for brake dressing compounds and particularly to an applicator for the dressing which may also be used as a clearance gauge between 5 brake linings and drums.

In applying dressings to brake linings it has heretofore been customary to squirt an undetermined amount of the dressing into the spaces between the brake linings and 10 drums. In applying dressing in this manner there is a tendency to continue the application of the dressing until it drips off from the brake, thereby wasting an appreciable quantity of the dressing. In applying the 15 dressing by a squirting or dripping operation, no consideration has heretofore been given the clearance existing between the brake drum and the brake lining. For efficient operation of the brake it is essential 20 that a definite clearance be had when the brake is in its released position.

I provide an applicator whose surface area is designed to retain the proper quantity of dressing for a single application of the 25 dressing to brake lining. In designing the area of the applicator, the viscosity of the dressing is considered, as well as the actual weight of the dressing desired in an application. The applicator preferably comprises a 30 flat, pliable strip of metal the thickness of which is made such as to enter between a brake lining and drum if the proper clearance 35 between them exists. If the brake lining is too loose, the applicator serves to indicate the amount in which it should be drawn up. The applicator is carried by the stopper for a dressing container and when 40 not in use extends downwardly into the container. The depth of the container is made such that the applicator may reach to its bottom.

The accompanying drawings illustrate the present preferred embodiment of the invention, in which,—

45 Figure 1 is an elevational view of a container embodying my invention; and

Figure 2 is a view, partially in elevation and partially in section, of an applicator embodying my invention.

Referring to the drawings, the applicator 50 is a thin strip of metal inserted in a stopper 4 for a container 5. The applicator extends downwardly into the liquid brake dressing 6 in the container.

In applying the liquid 6, the applicator 2 55 is removed from the liquid and inserted between a brake lining and drum. The amount of liquid 6 adhering to the surfaces of the applicator is predetermined by the viscosity 60 of the liquid and by the area of the applicator. Preferably the amount is sufficient for a complete application of the dressing. If the clearance between the brake drum and lining is too small for efficient operation of the brakes when released, the thickness of the applicator prevents its insertion 65 between them. If too much clearance exists between the brake lining and drum, this condition is indicated by an excessive amount of play between the applicator 2, the lining and 70 the drum.

While I have shown and described the applicator as of metal, it is to be understood that other materials such as celluloid, and the like, may be substituted therefor without departing from the scope of the appended claims.

I claim:

1. A liquid applicator comprising a thin metallic strip whose thickness is predetermined in accordance with the clearance desired between a brake drum and lining.

2. A liquid applicator comprising a thin metallic strip whose thickness is predetermined in accordance with the clearance desired between a brake drum and lining, and whose surface area bears a definite relation to the amount of liquid to be applied to a brake lining at each application.

In testimony whereof I have hereunto set 90 my hand.

JAMES W. MOOREHEAD.
